(57) **CLAIM**

The ornamental design for a lid for containers, as shown and described.

DESCRIPTION

FIG. 1 is a front perspective view of a lid for containers embodying our new design;
FIG. 2 is a front side elevation view thereof;
FIG. 3 is a rear side elevation view thereof;
FIG. 4 is a right side elevation view thereof;
FIG. 5 is a left side elevation view thereof;
FIG. 6 is a top plan view thereof; and,
FIG. 7 is a bottom plan view thereof.
The broken lines shown in FIG. 7 represent unclaimed subject matter and form no part of the claimed design.
